UNITED STATES PATENT OFFICE.

SILAS G. AUSTIN, OF BOSTON, ASSIGNOR TO ANNIE E. AUSTIN, OF MALDEN, MASSACHUSETTS.

FASTENER FOR MEETING-RAILS OF SASHES.

SPECIFICATION forming part of Letters Patent No. 250,479, dated December 6, 1881.

Application filed May 2, 1881. (Model.)

To all whom it may concern:

Be it known that I, SILAS GRANVILLE AUSTIN, of Boston, in the county of Suffolk and State of Massachusetts, have invented a new 5 and useful Improvement in Sash-Fasteners, of which the following is a full, clear, and exact description.

Figure 1 is a sectional plan of a window frame and sashes to which my fastener is applied. Fig. 2 is an enlarged transverse section on the line $x x$, Fig. 1. Fig. 3 is a front elevation of the locking-plate O as applied to the sash.

Similar letters of reference indicate corresponding parts.

The object of my invention is to provide an improved sash-fastening device which can be easily applied to window-sashes, and constitutes an easily-operated and effective lock for the same.

Referring to the drawings, A represents a window-frame in which the lower sash, B, and upper sash, C, are adjusted. The parting-strips a, secured in grooves in both sides of the frame B, guide the sashes in the frame, and the cross-bars c make a joint between the meeting-rails of the sash, when they are closed, in the usual manner.

The base-plate D of my fastener is fixed to 30 the upper face of the top rail of the lower sash, B, by screws d or other suitable fastenings. From the plate D rise pins or studs e, which support the spiral springs f, which are coiled around the studs loosely. Said studs e also 35 afford a means of fastening the cap-plates g by means of screws h, which are threaded into the body of the studs, as shown, said plates g serving to protect the internal spring and axial joint from dust, and also act within a corresponding recess in the upper faces of the spring-catches E E' to hold the annular rib e', formed upon the lower side or face of said catches, into corresponding recesses d', formed in the upper face of the base-plate D, in which recesses the ribs e' are loosely fitted, the joint of e' with d' 40 forming the vertical axis on which the spring-catches E E' are free to oscillate in a horizontal plane.

The opposite ends of the coiled springs f are seated in bearings in the catches E E' and base-plate D, respectively, said springs tending to force the outer locking ends or arms, i, of the catches inward against the stop k, which rises from the base-plate D, the inner ends or arms, I, of the catches affording means of grasping them to release them from the arrow-headed locking-plate O, which latter is secured to the face of the bottom or meeting rail of the upper sash, C, by screws o. Said locking-plate O is not thicker than the parting-strips a or meeting-rail bars c, and the ends of the locking-arms i not extending past the face of the upper sash, both upper and lower sashes may be raised or lowered their entire length past each other after the spring-catches E E' are released from the locking-plate by their partial rotation, as shown in dotted lines in Fig. 1. Upon opening either sash the stop k will hold the locking-arms i of the catches a proper distance apart to cause the beveled edges of said arms i to 50 act upon the inclined sides o' of the arrow-head upon the partial closing of the sashes and automatically open said catches E E', as in dotted lines, and upon a tight closure of the sashes permit their arms i to spring in underneath the shoulders o' of the arrow-headed lock O, which movement will automatically and firmly 55 lock both sashes closed.

If the plates D and O are properly adjusted to the sashes, it will be difficult to introduce a thin blade or knife between them to release 60 the fastenings.

The construction of my fastener is such that it can be readily fixed to two light sashes opposite their center vertical dividing-rails, in 65 which position a sash-fastener properly belongs to preserve the symmetrical appearance of the window; and instead of fixing a locking-plate to the upper face of the meeting-rail of the upper sash by small screws, as is fastened 70 the horizontal plate of ordinary window-fastenings, which may be easily forced off, I am enabled to fasten my locking-plate O onto the face of the meeting-rail with such large and strongly-holding screws that any attempt to 75 force it off by prying up the lower sash would 80

most likely demolish the glass in the sash and alarm the occupants of the house.

It is evident that, if so desired, a single spring-catch, E, may be employed with a base-
5 plate, B, and stop k instead of two such catches, as shown, in which case the locking-plate O would be provided with a single corresponding inclined side, O', and shoulder o²; but I prefer to use the double catch and lock, as
10 above described.

Having thus fully described my invention, what I claim as new, and desire to secure by Letters Patent, is—

In sash-fasteners, the combination, with the plate D, having stop k, recess d', hollow studs 15 e, carrying loose springs f, the cap-plates g, and the screws h, of the spring-catches E E', having annular rib e', and outer locking-arms, i, and the arrow-head plate O, having inclined sides o' and shoulders o², as shown and de- 20 scribed.

SILAS GRANVILLE AUSTIN.
